6 Claims. (Cl. 250—27)

This invention pertains to pulse shaping circuits and more particularly relates to an electronic circuit responsive to a pulse or train of input pulses of varying amplitudes for generating a corresponding pulse or train of output pulses of uniform and predetermined amplitude. The novel circuit is capable of generating rectangular pulses having steep leading and trailing edges.

The invention makes use of the properties of certain magnetic materials characterized by a rectangular hysteresis loop providing two identifiable stable states of magnetization and providing a highly non-linear flux density-coercive force relationship whereby the state of magnetization can be definitely and quickly changed. The invention utilizes a magnetic core transformer having its secondary winding connected in series with the load and having a constant D.C. biasing current applied to its primary winding to cause the magnetic core to be held at one of its two stable states of magnetization. An input pulse causes a rapidly increasing current to flow in the secondary winding until the magnitude of that current causes the magnetic core to commence changing its state of magnetization. At this point a large change in magnetic flux occurs in the core inducing a back E.M.F. in the secondary winding which tends to oppose any further increase of current and maintain the secondary winding current at a constant value. After termination of the input pulse, the D.C. biasing current in the primary winding causes the magnetic core to return to its initial state of magnetization. By virtue of this action, the novel pulse shaping circuit is capable of producing an output pulse having steep leading and trailing edges and having a predetermined amplitude. By adjustment of the D.C. biasing current flowing in the primary winding, the amplitude of the output pulse may be changed. The ease and rapidity with which the amplitude of the output pulse may be changed is an important attribute of this invention.

The invention and its mode of operation can be apprehended by reference to the following exposition when considered in conjunction with the drawings wherein:

Fig. 1 is a schematic representation of the preferred embodiment of the invention;

Fig. 2 is a diagram showing a rectangular hysteresis loop; and

Fig. 3 is a schematic representation of another embodiment of the invention.

Referring now to Fig. 1, there is illustrated a circuit for regulating the amplitude of a current pulse. A vacuum tube, here shown as a triode 1, has its cathode connected to ground through a resistor 2 in series with the secondary winding 3 of a transformer 4 having a core fabricated of magnetic material characterized by a rectangular hysteresis loop. In the primary winding 5 of the transformer, there is a large biasing current $I_{D.C.}$ supplied from a constant current D.C. source connected to terminals 6. A constant current generator may be any current generator whose internal impedance is high in relation to the impedance of the load supplied. The dots adjacent the windings of transformer 4, in accordance with conven-

2

tion, indicate that the primary and secondary windings are positioned around the core so that the same electrical polarity obtains at the dotted ends of those windings. A diode 7 is shunted across the ends of secondary winding 3 to permit electron flow to ground. The plate of tube 1 is connected to a source of B_+ voltage through the load which is connected across output terminals 8. The control grid of tube 1 is connected through resistor 9 to input terminal 10 and a diode 11 is provided to clamp the grid to ground when the input signal exceeds ground potential.

Fig. 2 shows the type of rectangular hysteresis loop which characterizes the magnetic core of transformer 4. The magnetic properties of the core material are defined by the way the flux density B is related to the applied magnetic field H . When the core is magnetized by an applied field, in the negative direction, for example, of sufficient magnitude to cause saturation, the core will retain the larger part of its magnetization when the applied field is removed. If the rectangularity were perfect the magnetic flux density $-B_s$ would be equal to the saturation flux density $-B_m$ and when once driven to saturation there would be no further change in the state of magnetization due to additional negative fields of any magnitude. Certain materials such as magnesium manganese ferrites, permalloy, nickel-iron alloys, and others exhibit a high degree of rectangularity. Because the magnetic core of transformer 4 is characterized by a rectangular hysteresis loop, the current $I_{D.C.}$ in primary winding 5 causes flux density saturation of the core and the initial operational point is established at the point 12 by the magnitude of the direct current. H_1 is the coercive force established by current flow in the primary winding, i.e.

$$H_1 = kN_1 I_{D.C.}$$

where k is a constant characteristic of the geometrical dimensions of the core, and N_1 is the number of turns in the primary winding.

In order to cause the magnetic core to change its state of magnetization, it is necessary to provide an opposing coercive force H_2 somewhat greater in magnitude than H_1 . When such an opposing coercive force is applied, a large and rapid change in flux occurs in the core. The opposing coercive force H_2 is generated in the circuit of Fig. 1 by causing current I_2 to flow in the proper direction in secondary winding 3 and $H_2 = kN_2 I_2$ where N_2 is the number of turns in the secondary winding, and I_2 is the current flowing in the secondary winding.

In the circuit of Fig. 1, tube 1 is cut off in the quiescent state by impressing a negative bias potential E_{cc} on the control grid. Because of the D.C. biasing current flowing in primary winding 5, the operating point of the core of transformer 4 is at point 12 of the hysteresis diagram.

When a positive pulse e_c is applied at input terminal 10, the control grid is driven to ground potential and kept at that potential by clamping diode 11. Current rapidly commences to flow through the tube since the secondary winding 3 offers but slight impedance due to saturation of the magnetic core. As tube current flow increases the operating point shifts to the right from point 12 and when the current I_2 in the secondary winding causes the coercive force H_2 to exceed H_1 , the operating point moves up the knee of the hysteresis curve toward point 13. When this occurs a high voltage develops across the secondary winding because of the rapid change in flux density in the magnetic core and consequently the voltage of the cathode is raised. The grid-cathode bias is thereby reduced sufficiently to cause the output current I_2 to remain almost constant. The output current will now tend to increase slowly but before the operating point reaches saturation in the positive direction ($+B_m$) the grid driving pulse e_c should be completed. The pulse e_c in the drawing is of such duration that the operating point moves

to point 13 on the hysteresis diagram before the pulse is terminated. Upon termination of the input pulse the tube 1 is again cut off and the collapsing field about the windings causes the diode 7 to conduct whereby the cathode is rapidly returned to ground potential. The biasing current in primary winding 5 concurrently causes the operating point to return to the initial point via path 13, 14, and 12 so that the circuit will be ready for another input pulse. Diode 7 is employed to prevent the cathode from dropping below ground level during the fall of I_L . Because of the rapid collapse of the magnetic field, ringing may be encountered in the cathode circuit and in this circumstance a resistor of appropriate value placed in series with diode 7 will damp out the undesired oscillations. The pulse shaping circuit provides a high degree of degeneration during the peak of the output current, and extremely small degeneration during the rise and fall of the output current, giving fast rise and fall times. Resistor 2 in the cathode circuit provides some degeneration and its function is to protect tube 1 from excessive plate current in the event that the control grid should be driven up for too long an interval.

The peak output current attained is

$$I_2 = \frac{N_1 I_{D.C.}}{N_2} + \frac{H_c}{kN_2}$$

where H_c is the coercive force of the core.

Using a core of low coercive force this is essentially

$$\frac{N_1 I_{D.C.}}{N_2}$$

The output current can be varied by changing $I_{D.C.}$ which determines the initial operating point 12. By decreasing $I_{D.C.}$ the initial operating point is moved to the right and the amplitude of the output pulse is decreased. As a corollary, increasing $I_{D.C.}$ causes the initial operating point to be moved to the left and the amplitude of the output pulse is increased. Since the output of a constant current generator may, in general, be easily regulated, the initial operating point of the core is readily changed to control the amplitude of the output pulse.

Fig. 3 illustrates a current amplitude regulating circuit which may be used where the impedance of the load and the input signal source are both very low. A biasing current $I_{D.C.}$ supplied by a constant current generator connected to terminals 15, is caused to flow in the primary winding 16 of transformer 17. The core of the transformer is constituted of a magnetic material of the type previously described having a rectangular hysteresis loop. The secondary winding 21 of transformer 17 is shunted by a rectifier 25 in series with a resistor 26. The input signal pulse e_c is applied at terminals 18 and a low impedance load, here indicated as a resistor 19, is connected across terminals 20 whereby the secondary winding 21 is in series with the load. The direction of current flow to and from the load is indicated by arrows labeled I_L . A rectifier 22, in series with secondary winding 21, prevents load current I_L from reversing. Where a rectifier may already be present in the load or the signal source, rectifier 22 may be eliminated.

The current $I_{D.C.}$ flows in the primary winding 16 in such direction as to cause the magnetic core of transformer 17 to be saturated in the plus direction and the initial operating point to be established at the point 23 indicated in Fig. 2. When the positive input pulse e_c is applied at terminals 18, it causes a rapidly increasing current I_L to flow in secondary winding 21 and when the coercive force due to the current flow in that winding exceeds the coercive force due to current $I_{D.C.}$ flowing in the primary winding, the operating point of the core moves down the knee of the hysteresis curve toward point 24. At this time a high back E.M.F. is induced across the secondary winding because of the rapid change in flux density in the core thereby opposing any additional increase of the current I_L . The current I_L will now tend to in-

crease slowly but before the operating point reaches saturation in the negative direction ($-B_m$) the input pulse e_c is completed. The diode 25 will now conduct current due to the collapse of the magnetic field about the transformer windings and the resistor 26 acts to prevent "ringing" or oscillations in the secondary winding 21. The diode 25 also acts as a safety device inasmuch as it prevents a high inverse voltage from being impressed across the rectifier 22 upon collapse of the magnetic field. The biasing current in primary winding 16 causes the operating point of the core to return to its initial position to prepare the circuit for the next input pulse.

While there has been described what is at present considered to be the preferred embodiment of this invention, it will be obvious to those skilled in the electronic circuit art that various changes and modifications may be made therein without departing from the scope of the invention as set forth in the appended claims.

What is claimed is:

20. A pulse shaping circuit comprising a transformer including a primary and a secondary winding and having a magnetic core characterized by a rectangular hysteresis loop, means for impressing a potential on said primary winding to cause a biasing direct current to flow therein, a unilateral impedance and a load connected in series with said secondary winding, and means for connecting an input signal source in series with said secondary winding.
25. A pulse shaping circuit comprising a primary and a secondary winding and a magnetic core, said magnetic core having a rectangular hysteresis loop, a direct current generator coupled to said primary winding whereby a biasing current flows in said primary winding causing flux density saturation in said core, a unilateral impedance and a load connected in series with said secondary winding, and means for connecting a source of input signals in series with said secondary winding, said input signals causing current to flow in said secondary winding in a direction such that the coercive force attributable to that current opposes the coercive force due to said biasing current in said primary winding.
30. An electronic circuit comprising a transformer including a magnetic core having a rectangular hysteresis loop, a direct current generator coupled to the primary winding of said transformer, an electron tube having a cathode, anode, and control grid, said cathode being connected through said secondary winding of said transformer to a reference potential, means coupled to said control grid for applying input signals, unilateral impedance means connected to said control grid for clamping said grid to said reference potential when said input signals exceed a predetermined potential, and means for connecting a load in series with said secondary winding.
35. A pulse shaping circuit comprising a transformer including a magnetic core of the type having a rectangular hysteresis loop, a constant current generator coupled to the primary winding of said transformer, a vacuum tube including a cathode, an anode, and a control grid, said cathode being connected through the secondary winding of said transformer to a reference potential, means connected to said control grid for clamping said grid to said reference potential when said input signals exceed a predetermined potential, and means for connecting a load in series with said secondary winding.
40. A pulse shaping circuit comprising a transformer including a magnetic core of the type having a rectangular hysteresis loop, a constant current generator coupled to the primary winding of said transformer, a vacuum tube including a cathode, an anode, and a control grid, said cathode being connected through the secondary winding of said transformer to a reference potential, means connected to said control grid for clamping said grid to said reference potential when said input signals exceed a predetermined potential, and means for connecting a load in series with said secondary winding.
45. A pulse shaping circuit comprising a transformer including a magnetic core of the type having a rectangular hysteresis loop, a constant current generator coupled to the primary winding of said transformer, a vacuum tube including a cathode, an anode, and a control grid, said cathode being connected through the secondary winding of said transformer to a reference potential, means connected to said control grid for clamping said grid to said reference potential when said input signals exceed a predetermined potential, and means for connecting a load in series with said secondary winding.
50. A pulse shaping circuit comprising a transformer including a magnetic core of the type having a rectangular hysteresis loop, a constant current generator coupled to the primary winding of said transformer, a vacuum tube including a cathode, an anode, and a control grid, said cathode being connected through the secondary winding of said transformer to a reference potential, means connected to said control grid for clamping said grid to said reference potential when said input signals exceed a predetermined potential, and means for connecting a load in series with said secondary winding.
55. A pulse shaping circuit comprising a transformer including a magnetic core of the type having a rectangular hysteresis loop, a constant current generator coupled to the primary winding of said transformer, a vacuum tube including a cathode, an anode, and a control grid, said cathode being connected through the secondary winding of said transformer to a reference potential, means connected to said control grid for clamping said grid to said reference potential when said input signals exceed a predetermined potential, and means for connecting a load in series with said secondary winding.
60. A pulse shaping circuit comprising a transformer including a magnetic core of the type having a rectangular hysteresis loop, a constant current generator coupled to the primary winding of said transformer, a vacuum tube including a cathode, an anode, and a control grid, said cathode being connected through the secondary winding of said transformer to a reference potential, means connected to said control grid for clamping said grid to said reference potential when said input signals exceed a predetermined potential, and means for connecting a load in series with said secondary winding.
65. A pulse shaping circuit comprising a transformer including a primary and a secondary winding positioned on a magnetic core of the type characterized by a rectangular hysteresis loop, a constant direct current generator coupled to the primary winding of said transformer, a vacuum tube including a cathode, an anode, and a control grid, said cathode being connected through said secondary winding to a reference potential, a unilateral impedance means connected to said control grid for clamping said grid to said reference potential, a unilateral impedance means shunted across said secondary winding, means for connecting a load in series with said secondary winding,
70. A pulse shaping circuit comprising a transformer including a primary and a secondary winding positioned on a magnetic core of the type characterized by a rectangular hysteresis loop, a constant direct current generator coupled to the primary winding of said transformer, a vacuum tube including a cathode, an anode, and a control grid, said cathode being connected through said secondary winding to a reference potential, a unilateral impedance means connected to said control grid for clamping said grid to said reference potential, a unilateral impedance means shunted across said secondary winding, means for connecting a load in series with said secondary winding,
75. A pulse shaping circuit comprising a transformer including a primary and a secondary winding positioned on a magnetic core of the type characterized by a rectangular hysteresis loop, a constant direct current generator coupled to the primary winding of said transformer, a vacuum tube including a cathode, an anode, and a control grid, said cathode being connected through said secondary winding to a reference potential, a unilateral impedance means connected to said control grid for clamping said grid to said reference potential, a unilateral impedance means shunted across said secondary winding, means for connecting a load in series with said secondary winding,

and a plate supply voltage source to which said anode is connected.

6. A pulse shaping circuit comprising a transformer having a primary and a secondary winding positioned on a magnetic core of the type having a rectangular hysteresis loop, a direct current generator coupled to the primary winding of said transformer, an electron tube including a cathode, anode, and control grid, said cathode being connected through said secondary winding to a reference potential, means coupled to said control grid for impressing input signals, a unilateral impedance coupled to said control grid for clamping said grid to said reference potential when said input signals exceed a pre-

5

determined potential, means for connecting a load in series with said secondary winding, a unilateral impedance shunted across said secondary winding, and means for coupling said anode to a plate voltage source.
